UNITED STATES PATENT OFFICE.

HENRY F. SHAW, OF BOSTON, MASSACHUSETTS.

VALVE-GEAR FOR OSCILLATING ENGINES.

SPECIFICATION forming part of Letters Patent No. 267,725, dated November 21, 1882.

Application filed April 24, 1882. (No model.)

To all whom it may concern:

Be it known that I, HENRY F. SHAW, a citizen of the United States, residing at Boston, in the county of Suffolk and State of Massachusetts, have invented a new and useful Improvement in Valve-Gear for Oscillating Engines, of which the following is a specification, reference being had to the accompanying drawings.

10 My invention relates to valve-gear for oscillating engines, particularly to such engines as are adapted to be employed for locomotives; and it consists in valve-gear having the movements derived from the driving-wheels, operated by 15 means of and embodying the mechanism hereinafter set forth, and specifically pointed out in the claims.

In the drawings, (two sheets,) Figure 1 is a side view, and Fig. 2 a plan view, of such parts 20 of a locomotive-engine embodying my invention as serve to illustrate the same. Fig. 3 is a side view, the cylinder and valve-chest being removed. Figs. 4, 5, 6, and 7 show details drawn on a larger scale.

25 Of the two driving-wheels on one side of the locomotive, one, A, is on the axle B and the other, C, is on the axle D. The boxes for these axles are connected to a frame, E. It is sufficient for the purposes of the present 30 description to show only the parts on one side of the locomotive, bearing in mind that I prefer to have the crank-pins on the one side of the locomotive set quartering with those upon the other side.

35 Between the driving-wheels A and C is pivoted the oscillating cylinder F, having trunnion a in box b connected with frame E, and trunnion c in box d, on the outer end of the curved arm or bent support e, fixed to the frame

40 E. There are two pistons in the cylinder F, which ply in opposite directions. One of the pistons has a rod, f, which connects with a cross-head, g, and the other piston a rod, h, which connects with a cross-head, i. The 45 cross-head g slides between and on the inner sides of ways or guides j, and the cross-head i on ways or guides k, said ways or guides being fastened rigidly at their inner ends to the oscillating cylinder. The crank-pin G, attached to the wheel A, passes through the cross-head g, and the crank-pin H, attached to the wheel C, passes through the cross-head i.

To the cross-head g is rigidly joined a projection or stand, J, and to the cross-head i a stand, K.

On the trunnion a is a sleeve, l, having the two arms L fixed thereto, the sleeve and arms forming a bar, which may have an oscillation on the trunnion a independent of the oscillation of the cylinder. At the outer end of one 60 of the arms L is pivoted a connecting-rod, M, the other end of this rod being pivoted in the stand J. To the outer end of the other arm L is pivoted a connecting-rod, N, this rod being pivoted at the other end in the stand K. 65 The end of each of these rods, which is pivoted to one of the stands J and K, might be pivoted directly on the adjacent crank-pin, though I prefer to pivot each rod to a cross-head or a stand thereon, since thus there will 70 be less movement and wear of the bearing in the rod. It will be readily seen that by this arrangement of the connected rocking arms L and connecting-rods M and N, wheels, crank-pins, or cross-heads thereon, the wheels must 75 revolve in unison.

Pivoted to the oscillating cylinder, or to a guide, j, and projection s attached thereto, is a rocking stand, O, which has extensions or arms m and n. To the arm m is pivoted at o 80 a rocking piece, P, having two extensions or arms, p and q. To the arm p is pivoted the outer end of the valve-rod Q, and to the other arm, q, is pivoted one end of a connecting-rod, R. The other end of this connecting-rod is 85 pivoted to the sleeve l, or a projection thereof. To the arm n of the stand O is pivoted one end of the connecting-rod S, the other end of this rod being on a pivot-pin, r, adjustable in the curved guide and stand T. 90 This guide and stand is firmly secured on the arm e, fixed to the frame E. The block and pivot-pin r and a similar block and pivot-pin on the opposite side of the locomotive—or this end of the connecting-rod S and of a similar 95 rod for a similar purpose on the opposite side of the locomotive—may be so connected by a cross rod or shaft that the two connecting-rods may be swung along the curved guides at the same time by means of a lever in the cab of 100 the locomotive. By means of this device two motions are combined in the movement of the valve in either direction, one mainly by means of the oscillating sleeve l, connecting-rod R,

and rocking piece P. This motion will be most rapid when the crank-pins G and H are passing across lines extending perpendicularly through the centers of the driving-wheels. The other 5 of said motions is by means of the oscillating cylinder or guide j, attached thereto, connecting-rod S, and the fixed guide and stand T. This motion will be the most rapid when the 10 crank-pins are crossing a line extending horizontally through the centers of the driving-wheels. In the former motion—namely, the one for which the connecting-rod R is employed—the valve is moved mainly at the time before opening and after closing the ports—that is, this motion gives the lap and lead to 15 the valve. In the latter motion—namely, the one for which the connecting-rod S is employed—the valve is moved over the ports—that is, by this motion the ports are opened 20 and closed. Thus the ports for the admission of steam to the cylinder and for the exhaust are opened promptly, and free passage is given to the steam in the most effective manner. By moving the end of the connecting-rod S at the 25 guide and stand T, on each side of the locomotive, toward the center of said guide the opening for the ports is decreased, and when said end of rod S is above said center the movement of the valve is reversed. In whatever 30 position the connecting-rod S may be swung, if the ports are opened at all—that is, if the said end of rod S is not in the center of guide T—they will be opened with the promptness and efficiency above mentioned. My device 35 for obtaining these movements of the valve may be modified in details of construction, and may be applied to a stationary as well as a locomotive engine having one or more oscillating cylinders, or an oscillating cylinder having but one piston, and my invention be involved.

I claim as my invention—

1. The combination of one or two arms, L, which with the sleeve l form a pivoted rod or bar, a rod, M or N, connecting said bar with a crank-pin, rocking piece P, pivoted on a rocking stand O, connecting-rod R, and the valve-rod, substantially as and for the purpose specified.
2. The combination of the oscillating cylinder, valve, and valve-rod, fixed stand T, connecting-rod S, rocking stand O, oscillating arm or sleeve l, pivoted to oscillate about the same central line as the cylinder, connecting-rod R, and rocking piece P, substantially as described.

50 55

3. The combination of these elements, namely: an oscillating cylinder having a valve-chest fixed thereto, an arm pivoted to oscillate about the same central line as that of the cylinder, but to oscillate independently of the cylinder, 60 and mechanism—as the rocking piece P and connecting-rod R—for obtaining motion of the valve by means of said oscillating arm, substantially as specified.

4. The combination of these elements, namely: an oscillating cylinder having valve-chest connected thereto to oscillate therewith, a fixed stand, the same being a slotted curved guide, whereby a pivot pin thereon may be slid while the engine is in operation to regulate the travel 70 of the valve in the manner specified, connecting-rod S, and rocking stand O, substantially as and for the purpose specified.

5. In combination, these elements, namely: an oscillating cylinder having a valve-chest 75 to oscillate therewith, a fixed stand, an arm pivoted on the same central line with that of the cylinder, but pivoted to oscillate independently of the cylinder, and mechanism described for connecting said fixed stand and said oscillating arm with valve-rod, to produce the resultant motion specified of the valve.

6. In combination with two driving-wheels on the same side of a locomotive, and arms or 80 a bar to be oscillated by means of rods connecting said arms or bars with the crank-pins on the driving-wheels, a cylinder and chest containing valve located to oscillate on a pivot having the same central line with that of said arms or bars, a fixed stand, and connecting- 85 rods and mechanism, substantially as described, for connecting said oscillating arms, cylinder, and fixed stand with said valve, for the purpose set forth.

HENRY F. SHAW.
